UNITED STATES PATENT OFFICE.

ALEXANDER LIGGET, OF PHILADELPHIA, PENNSYLVANIA.

DYEING-MACHINE.

992,365.

Specification of Letters Patent. Patented May 16, 1911.

Application filed February 24, 1910. Serial No. 545,731.

To all whom it may concern:

Be it known that I, ALEXANDER LIGGET, a citizen of the United States, residing at Philadelphia, in the county of Philadelphia and State of Pennsylvania, have invented a certain new and useful Improvement in Dyeing-Machines, of which the following is a specification.

My invention relates to a new and useful improvement in dyeing machines, and has for its object to provide a tank or vat in which a slow revolving open frame work carrying baskets whose sides and ends are formed of wire netting, and to revolve said open frame work at a low rate of speed while the centrifugal blades which pass through the center of the open frame work are revolved at a high rate of speed so as to throw the dye liquid outward with sufficient force to drive it into the articles contained in the open frame work, thus effecting a more even dyeing action than is usually the case, and a still further object of my invention is to draw air from the vat, extract the moisture therefrom, heat this air to a high degree and force it into the vat below the liquid level, thus heating and agitating the liquid and causing it to flow from the articles to be dyed in the most effective manner.

Another object of the invention is to so construct the wire baskets that they may be readily placed in position, or quickly removed when necessary to do so, and another object is to provide said baskets with a swinging door so that the goods which are being dyed may be removed and other goods placed in the baskets without taking said baskets from the open frame work.

With these ends in view, this invention consists in the details of construction, and combination of elements hereinafter set forth and then specifically designated by the claims.

In order that those skilled in the art to which this invention appertains may understand how to make and use the same, I will describe its construction in detail, referring by letter to the accompanying drawing forming a part of this specification, in which—

Figure 1 is a front elevation of my improved dyeing machine, portions thereof being broken away shown in section to clearly illustrate the working of the device. Fig. 2,

a vertical sectional view thereof at the line ⁵⁵ *x—x* of Fig. 1, and Fig. 3, a perspective view of one of the baskets.

In carrying out my invention as here embodied, A represents a dyeing vat which may be constructed in any ordinary manner, but preferably having a metal frame B, on which is mounted the wooden walls C. This vat is provided with a door D, hinged at E, and to the free end of said door is fastened a baffle plate F, which rests upon the upper edge of the front wall and will shed the dyeing liquid therefrom, preventing it passing through the crack left between the door and the top of the front wall.

G represents a number of brackets secured to the bottom and side walls of the vat within the same, and in these frames are journaled the rolls H, and on these rolls is mounted the open frame work I, which is composed of a plurality of spiders J, the two end ones having gears K formed upon their periphery, but where this open frame work consists of more than two spiders, the central spiders do not have gears formed thereon. Further, the end spiders have a groove L formed around their periphery which registers with the rolls H. Each of these spiders has a circular opening O and these are connected by bars or rods M and N. Through the open frame work passes the shaft P which is journaled in suitable bearings Q mounted in the end walls of the vat, and these bearings are packed with the packing box R in the ordinary manner. On this shaft within the vat are mounted the centrifugal blades S, said shaft having power transmitted thereto through the gear wheels T or pulleys, and are driven at a very high rate of speed.

On the open frame work are mounted a number of wire baskets U, each of which is composed of a bottom, sides, ends and top of wire screen or its equivalent, such as perforated sheet metal, and to the top of each of said baskets is hinged a door V also of wire screening by means of the hinges W, and this door is held closed by any suitable means, such as the well known spring catch.

In proximity to each end of the bottom of the baskets is mounted a bar Z, portions of which are bent inward to form the recesses A', said recesses engaging the rods N,

and on the top of each of these baskets in proximity to both ends is mounted a fastening member B' composed of two sections C', and to one of these members is pivoted a 5 plate D' by means of the stud E' or its equivalent, said plate being provided with a slot F' adapted to register with the thumb screw G' mounted in the end of the adjacent member C', thus when the plate D' is fastened 10 in position the members C' virtually form a single piece. The outer ends of said members are bent to form the hooks H' which engage the rods M, thus holding the baskets securely to the open frame work. 15 The open frame work is slowly revolved by the pinions I' meshing with the gears K, said pinions being mounted upon shaft J' which is journaled in suitable bearings K' mounted on the sides of the vat, and on the 20 outer ends of said shaft are mounted the gear wheels L', through which power is transmitted to the pinions. This rotation of the open frame work will successively submerge and elevate the articles being 25 treated, and as the level of the dye liquid is approximately on the line with the shaft P, ample space is provided above the liquid level to hold the articles being treated for a sufficient length of time in the hot air and 30 vapor above the liquid level which greatly facilitates the penetrating and setting of the dye.

M' is a pipe which leads to the lower portion of the vat from the funnel or holder N' 35 for adding additional dye from time to time as occasion may require, and below this funnel is placed a valve O' for controlling the same. P' is another pipe leading to the pipe M' whereby water or stored dye 40 liquid may be placed in the vat when necessary.

Connected with the top of the vat is a hood Q' from which leads the pipe R' to a heater S' having a coil T' or its equivalent, 45 between each section of which is mounted a baffle plate U'. Leading to the coil is a pipe V' from a suitable boiler, and from this coil leads a pipe W' to the manifold Y' at the lower portion of the vat and used 50 for holding the dye liquid within said vat. From the heater leads a pipe Z' to the pump A² and a pipe B² leads from this pump to the pipe C² within the vat situated below the liquid level, and this pipe 55 C² is slotted or may have small holes D² formed therein, which, when the air issues therefrom will force the surrounding liquid upward in jets against the baffle plate E², having a depending extension F², therefore 60 said baffle plate will deflect these jets coming in contact therewith downward, causing the liquid to flow over the articles contained in the baskets, and as the cylinder carrying said baskets is revolving, all the articles 65 contained in said baskets will be subjected

to this treatment which will further increase the efficiency of the apparatus.

Any suitable outlet G² may be provided for drawing off the liquid from the vat when occasion requires. 70

The operation of the device is as follows: The articles to be dyed are placed in the wire baskets U, which are mounted upon the open frame work I; then said open frame work is revolved at a moderate rate of 75 speed, while the centrifugal blades S are revolved at a relatively fast speed, thus the articles within the baskets are submerged and at the same time the dye liquid is forced into them by the centrifugal blades. When 80 the pump A² is in operation the air and moisture is drawn from the upper portion of the vat through the heater where it is raised in temperature by the heat from the steam passing through the coil T', after 85 which it is driven through the pipe B² back to the vat. The steam which heats the coil passes from the heater through the pipe W' into the imperforated manifold Y' so that 90 the dye liquid is held at a normal temperature. 95

Of course I do not wish to be limited to the exact details of construction here shown, as these may be varied within the limits of the appended claims without departing from the spirit of my invention.

Having thus fully described my invention, what I claim as new and useful, is—

1. In a dyeing machine, a vat, an open frame work revolvably mounted in the vat, wire screen baskets, means for detachably securing said baskets to the open work, means for revolving said open work, and centrifugal blades revolvably mounted within the vat for forcing the dye liquid away from 100 the center of the open work. 105

2. In combination, a vat, an open frame work having perforated baskets mounted thereon, means for revolving said open frame work relatively slowly, centrifugal blades mounted within the open frame work, and means for revolving said blades relatively fast. 110

3. In combination, a vat, an open frame work revolvably mounted in said vat, perforated baskets having recesses formed in the bottom thereof for engaging a portion of the open frame work, fastening members mounted upon the top of the baskets, each of said members comprising two sections, each of said sections having a hook bent therefrom, said hooks adapted to engage a portion of the open frame work for holding the baskets in place, and means for revolving the open frame work. 115 120

4. In combination, a vat, an open frame work composed of a number of spiders, rods for fastening said spiders together, perforated baskets having recesses formed in the bottoms thereof, said recesses adapted to 125 130

- register with a number of the rods joining the spiders, fastening members mounted upon the top of the baskets, each of said members comprising two sections, each section having a hook formed therefrom, said hooks adapted to engage other rods which join the spiders, thereby holding the baskets in place, and means for joining the adjacent sections of each fastening member.
- 5 5. In combination, a vat, an open frame work composed of a number of spiders, rods for fastening said spiders together, perforated baskets having recesses formed in the lower edges thereof adapted to engage a 10 number of the rods which join the spiders, a pair of fastening members mounted on top of each basket, each of said fastening members comprising two sections, each section having a hook formed therefrom adapted to 15 engage other rods which join the spiders, a plate having a slot pivoted to one of the sections of each of the fastening members, and a thumb screw mounted in the adjacent section adapted to register with the slot in the 20 plate.
- 25 6. In combination, a vat, a door hinged thereto, a baffle plate mounted upon said door adapted to extend over the meeting edges of said door and the front wall of the 30 vat, a number of brackets mounted within the vat, rolls journaled in said brackets, an open frame work composed of a number of spiders, the end spiders having gear teeth formed upon their periphery, pinions meshing with the gear teeth for revolving the 35 open work frame, perforated baskets detachably mounted upon the open frame work, a shaft journaled in suitable bearings passing through the center of the open frame work, 40 means for revolving said shaft, and centrifugal blades mounted upon said shaft within the open frame work.
7. In combination, a vat, a door hinged thereto, a baffle plate mounted upon said door, overlapping the upper edge of the 45 front wall of the vat, a number of brackets mounted within the vat, rolls journaled in said brackets, an open frame work comprising a number of spiders, the end spiders having gear teeth formed upon their periphery and adapted to rest upon the rolls, pinions meshing with the gear teeth for revolving the 50 open frame work, perforated baskets detachably mounted upon the open frame work, a shaft journaled in suitable bearings passing through the side walls of the vat and through the open frame work, means for revolving said shaft, centrifugal blades mounted upon said shaft within the open frame 55 work, a hood mounted on top of the vat, a heater, a pipe leading from the hood to said condenser, a pump, a pipe leading from the heater to said pump, a perforated pipe mounted within the vat below the normal level of the dye liquid, another pipe connecting the perforated pipe with the pump, a baffle plate having a depending projection mounted within the vat above the perforated pipe for deflecting the liquid issuing from 60 said perforated pipe, a steam pipe leading to the heater, an imperforated manifold mounted within the vat, and a pipe leading from the heater to said manifold.
- 70 In testimony whereof, I have hereunto affixed my signature in the presence of two 75 subscribing witnesses.
